Inventor

UNITED STATES PATENT OFFICE.

FREDERICK OLSON, OF CALUMET, MICHIGAN.

FLUE-SCRAPER.

SPECIFICATION forming part of Letters Patent No. 727,994, dated May 12, 1903.

Application filed August 11, 1902. Serial No. 119,344. (No model.)

To all whom it may concern:

Be it known that I, FREDERICK OLSON, a citizen of the United States, residing in Calumet, in the county of Houghton, State of Michigan, have invented a Machine for Scraping Flues; and I do declare the following to be a full, clear, and exact description of the invention, reference being had to the accompanying drawings, which form a part of this specification.

My invention has relation to flue-scrappers; and it consists in the novel construction and arrangement of its parts, as hereinafter described.

The object of the invention is to provide a scraper having adjustable scraping-plates adapted to operate in flues of various sizes. The scraper may be located permanently in the flue without interfering with the draft thereof and may be operated periodically for cleaning the flue. It also permits the flue to be cleaned without the operator going upon the roof.

The device is simple and strong in construction, and is easily operated, and does not damage the lining of the flue while in operation.

In the accompanying drawings, Figure 1 is a plan view of the top part of the device. Fig. 2 is a side elevation of the device. Fig. 3 is a top plan view of one of the strip-supports. Fig. 4 is a top plan view of the scraper plates or blades. Fig. 5 is a longitudinal sectional view of a casting used on the top part of the device. Fig. 6 is a transverse sectional view of the casting shown in Fig. 5. Fig. 7 is a sectional view of one of the plates for securing the scraper-blades together. Fig. 8 is a side elevation of a pin for securing the blade-retaining plates together. Fig. 9 is a sectional view of another blade-retaining plate used in the invention. Fig. 10 is a transverse sectional view of a roller used in the top part of the device.

The device consists of the top 1, which is provided at its middle with a casting 2, in which is journaled a roller 3. The said casting 2 at its longitudinal edges is provided with the flanges 4 and just above said flanges with the grooves 5. The inner ends of the metallic strips 6 are bifurcated and are adapted to fit in the grooves 5, said inner ends being provided with the perforations 7, which

are adapted to receive the ends of the inverted-U-shaped staples 8, the middle portion of said staples passing over the top of the casting 2 and being secured against the under side of said casting by means of nuts 9. The outer ends of the strips 6 are bent at an angle, as at 10, and are adapted to pass down along the sides of the upper edges of the flue. The periphery of the wheel 3 is grooved, and the endless chain 11 passes over said wheel in said groove. It will be seen that the strips 6 may be adjusted in or out, according to the breadth of the flue, and when properly adjusted are firmly held in proper positions relative to each other by means of the securing-staples 8. The scraper proper consists of the scraper-plates 11, each of which is provided with two parallel bars 12, the inner ends of said bars being adapted to enter grooves 13 and 14 of the retaining-plates 15 and 16, respectively. The plate 15 is provided with an eye 17 to which one end of the chain 11 is linked to the pin 18, passing through a central perforation of the lower plate 16, and screws into a socket in the upper plate 15. Thus the said plates 15 and 16 are secured together, holding the bars 12 between them. The pin 18 is provided with an eye 19, to which is linked the opposite end of the chain 11. The perpendicular portion of the said chain, which is directly opposite the plates 15 and 16, passes through the scraper proper in the space between the bars 12. It will thus be seen that the scraper-blades 11 may be adjusted in or out to fit the flue.

I do not bind myself to any particular size for the parts of my invention, as dimensions may be varied to meet the required strain. The top of the scraping apparatus being firmly secured at the top of the chimney-flue and the endless chain being of sufficient length is dropped down the chimney.

To operate the device, the operator pulls alternately at either side of the chain, and this causes the scraping-blades to pass the entire length of the flue, and a thorough cleaning is accomplished. The apparatus can be left hanging in the flue ready for use or can be easily removed after the flue is cleaned.

Having described my invention, what I claim as new, and desire to secure by Letters Patent, is—

A flue-cleaner comprising a top part having a central casting with a roller journaled therein, said casting having at its lower edges longitudinal flanges with grooves located 5 above the same, strips adapted to be secured at their ends to the flue and being bifurcated at their inner ends, said bifurcation adapted to enter grooves of the castings, a means for securing said strips to the castings and a

chain passing over said roller and carrying 10 suitable scraping-blades.

In testimony whereof I affix my signature in presence of two witnesses.

FREDERICK OLSON.
